CLAIM

The ornamental design for an automobile trunk lid antenna mount, as shown and described.

DESCRIPTION

FIG. 1 is a perspective view of a automobile trunk lid antenna mount showing my new design, taken from the top, front and right side of the stand;

FIG. 2 is a perspective view of the stand taken from the bottom, rear and left side of the stand;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

FIG. 1**FIG. 2****FIG. 3****FIG. 4****FIG. 5****FIG. 6****FIG. 7****FIG. 8**
